CLAIM

The ornamental design for a light, as shown and described above.

DESCRIPTION

FIG. 1 is a front perspective view of a light of the present invention;

FIG. 2 is a front elevation view of the light shown in FIG. 1;

FIG. 3 is a rear elevation view of the light shown in FIG. 1;

FIG. 4 is a right-side view of the light shown in FIG. 1;

FIG. 5 is a left-side view of the light shown in FIG. 1;

FIG. 6 is a top view of the light shown in FIG. 1;

FIG. 7 is a bottom view of the light shown in FIG. 1;

FIG. 8 is a top perspective view of the light shown in FIG. 1;

FIG. 9 is a front perspective view of a second exemplary light of the present invention;

FIG. 10 is a front elevation view of the light shown in FIG. 9;

FIG. 11 is a rear elevation view of the light shown in FIG. 9;

FIG. 12 is a right-side view of the light shown in FIG. 9;

FIG. 13 is a left-side view of the light shown in FIG. 9;

FIG. 14 is a top view of the light shown in FIG. 9;

FIG. 15 is a bottom view of the light shown in FIG. 9;

FIG. 16 is a top perspective view of the light shown in FIG. 9;

FIG. 17 is a front perspective view of a third exemplary light of the present invention;

FIG. 18 is a front elevation view of the light shown in FIG. 17;

FIG. 19 is a rear elevation view of the light shown in FIG. 17;

FIG. 20 is a right-side view of the light shown in FIG. 17;

FIG. 21 is a left-side view of the light shown in FIG. 17;

FIG. 22 is a top view of the light shown in FIG. 17;

FIG. 23 is a bottom view of the light shown in FIG. 17; and,

FIG. 24 is a top perspective view of the light shown in FIG. 17.

(Continued)

The broken lines are for illustration only and form no part of the claimed design.
